(57) **ABSTRACT**

A double-bell siphon for liquid flow control that improves upon existing bell siphons by the addition of an outer bell which helps the bell siphon to stop siphoning when the liquid level drops below the intended level. Optionally, a cup further enhances the ability for the siphon to stop properly.

AUTOMATIC DOUBLE-BELL SIPHON

TECHNICAL FIELD

A siphon moves liquid upward above the surface of a reservoir without using a pump. A bell siphon automatically starts and stops the siphoning action as the liquid level in the reservoir rises and falls. Bell siphons are used in a variety of fluid flow applications including wastewater discharge, restroom fixtures, and water flow in hydroponic and aquaponic systems.

BACKGROUND

Historically, the bell siphon has had two parts. The first is the upright, inner standpipe through which a liquid will drain out of the surrounding reservoir. The second part is the bell, which is typically a PVC pipe or a metal tube with a cap on the top, through which no liquid can escape. It also has one or more openings cut into the perimeter on the bottom so that liquid and air can flow through as it stands on the reservoir bed. When the liquid level reaches the height of the standpipe, the liquid and air flow into the standpipe creating a lower pressure inside of the bell. This causes liquid to be siphoned out of the reservoir and into the standpipe. The level drops until the liquid level reaches the level of the opening(s) at the bottom of the bell. At this point, air flows into the bell, breaking the siphon effect. The reservoir can now fill with liquid again.

Ideally, the bell siphon breaks its siphon effect every time the liquid level drops to the level of holes on the bottom. However, the air flowing into the bell may be carried by the moving liquid out the standpipe. If this occurs, the liquid level will remain at the low level in the reservoir and the siphon will never stop.

The bell siphon is a traditional way of automatically regulating liquid reservoir levels to keep a fill-drain cycle running repeatedly. For example, U.S. Pat. No. 649,170A, "Automatic Siphon," discloses an early automatic siphon design that was used for the flushing of sewers; it consists of the traditional bell and standpipe. US20220356691A1, "Underground Stormwater Storage System," discloses a similar use of a bell siphon in a stormwater storage system. US20130047508A1, "Aquaponics System" discloses a bell siphon for regulating water level in the plant bed of an aquaponics system.

However, there are disadvantages to this conventional bell siphon design in all these applications. First, if the liquid flow rate into the reservoir is too low then the bell siphon will fail to start the siphon effect. Second, if the flow of liquid is too high, the bell siphon will never stop. This range of flow rates where the siphon will both start and stop is limited.

Other attempts to provide reliable siphoning include U.S. Pat. No. 9,565,811B2, "External Cultivation liquid siphon," which implemented a U-tube shaped bell siphon in an aquaponics system. Another common addition is a small straw, also referred to as a snorkel, that runs up the side of the bell siphon external to the bell and allows an alternate path for air to enter. A cup around the snorkel provides some additional benefits, as seen in "Construction of Automatic Bell Siphons for Backyard Aquaponic Systems" by Bradley K. Fox, Robert Howerton, and Clyde S. Tamaru, University of Hawai'i at Mānoa, Department of Molecular Biosciences and Bioengineering, 2010 (<https://www.ctahr.hawaii.edu/oc/>

freepubs/pdf/BIO-10.pdf). However, a snorkel allows only a limited amount of air to enter. A small-diameter snorkel is also susceptible to clogging.

SUMMARY

Our dual-bell siphon replaces the snorkel with a second outer bell that wraps around the entirety of the inner bell (360 degrees), providing better air intake and less chance of clogging, while also allowing a smaller overall diameter of the device. The optional surrounding cup further enhances the airflow to stop the siphon.

BRIEF DESCRIPTION OF THE DRAWINGS

FIG. 1 (PRIOR ART) shows a typical application of a bell siphon, an aquaponic system with the bell siphon in the grow bed.

FIG. 2 (PRIOR ART) is an isometric view of the traditional bell siphon.

FIG. 3 (PRIOR ART) is a cross section view of the traditional bell siphon. The inner standpipe's perimeter is surrounded by the bell with an annular space between.

FIG. 4 (PRIOR ART) depicts a bell with a snorkel tube to enhance the intake of air and the stopping of the siphon. The snorkel tip is at the level of or higher than the highest opening in the bell.

FIG. 5 is an isometric view of the double-bell siphon.

FIG. 6 is an isometric view of the double-bell siphon with the optional cup.

FIG. 7 is a cross-sectional view of the double-bell siphon.

FIG. 8 is an exploded view of the double-bell structure with the optional cup. The standpipe is omitted from this drawing.

DETAILED DESCRIPTION

FIG. 1 (PRIOR ART) shows the common bell siphon as it is used in an aquaponic grow bed, a typical application. The bell siphon automatically regulates the water level in the grow bed, causing it to rise and fall periodically. The bell siphon 1, allows water to flow through it down into the fish tank 2.

FIG. 2 (PRIOR ART) is a depiction of the traditional bell siphon. The bell 4 has cap 5 fastened at the top. The bell 4 surrounds the standpipe 3. The cutout holes on the bottom of the bell 4 allow for air and water to enter the bell.

FIG. 3. (PRIOR ART) depicts a cross section of the traditional bell siphon.

FIG. 4 (PRIOR ART) depicts a bell with a snorkel tube 6 to enhance the intake of air and the stopping of the siphon.

FIG. 5 is the new double-bell siphon. The added outer bell 4 has a cap 5 on the top and a 360-degree aperture for air intake at the bottom. The inner bell 8 stands on the floor of the liquid reservoir surrounding the standpipe 3. The outer bell 4 is mounted above and surrounds the inner bell 8. The bottom of the outer bell 4 is at or above the highest opening in the inner bell 8 bottom end. The outer bell 4 acts as a large snorkel and allows a large volume of air to travel up to the top of the inner bell 8. The air bubbles brought to the top of the inner bell 8 allow for a more consistent siphon break. The outer bell 4 can be mounted in a variety of ways. In our preferred embodiment we use a spacer 7 to support the outer bell 4 while allowing fluids to flow. Alternately, the outer bell 4 could sit directly on top of the inner bell 8, with openings around the perimeter of the inner bell 8 at the top to allow fluids to enter.

FIG. 6 is an isometric view of the new double-bell siphon with the optional cup 9. The spacer 7 keeps the cap from resting directly on top of the inner bell 10. The spacer 7 has one or more apertures which allow air to travel directly to the top of the inner bell and break the siphon. The inner bell 10 rests on the cup 9. When using a cup 9, the inner bell 10 does not require openings in the perimeter at the bottom as in FIG. 5 because water is able to flow up into the inner bell 10 through an opening in the cup. The cup 9 must have one or more openings in its base to allow fluids to enter the base and flow up into the inner bell 10.

The purpose of the optional cup 9 is to separate a select volume of water from the rest of the tank. As the water level drops below the lip of this cup, the water inside the cup separates from the entire liquid reservoir. This creates a set volume of water that once siphoned through the outer bell cannot be replaced by water from the reservoir. This means that the siphon will more reliably stop.

PVC plastic is the recommended material for the bells. Although any engineer or designer with proper resources could create a bell siphon in another plastic, such as CPVC or acrylic, or metal, we built the bells with Schedule 40 PVC. The spacer 7 and the cup 9 may be 3D-printed out of PLA, ABS, or other plastic.

FIG. 7 is a cross-sectional view of the double-bell siphon design depicted in FIG. 6.

FIG. 8 is an exploded view of the double-bell structure. The standpipe is omitted from this drawing.

We claim:

1. An automatic double-bell siphon, comprising:
  - a. a standpipe installed in a floor of a liquid reservoir;
  - b. an inner bell consisting of a single unitary conduit that abuts the floor of the liquid reservoir and surrounds said standpipe with an annular space between said inner bell and said standpipe and which has an opening at a top end for fluids to enter and one or more openings at a bottom end for fluids to enter, wherein said one or more openings pass through a wall of the bottom end;

c. an outer bell closed at a top end and open at a bottom end which covers and surrounds said inner bell with an annular space between said outer bell and said inner bell and which provides a channel for fluids to flow from a surrounding liquid reservoir into said inner bell.

2. The automatic bell siphon of claim 1, wherein said outer bell is mounted on top of said inner bell with a spacer abutting a top of said inner bell and abutting and supporting an inner surface of a cap connected to said outer bell.

3. An automatic double-bell siphon, comprising:

- a. a standpipe installed in a floor of a liquid reservoir;
- b. a cup that abuts the floor of the liquid reservoir and surrounds said outer bell said standpipe with an annular space between said cup and said standpipe and which has one or more openings in a base of the cup to allow fluids from the liquid reservoir to enter the base of the cup;

c. an inner bell consisting of a single unitary conduit that abuts the cup and surrounds said standpipe with an annular space between said inner bell and said standpipe and which has an opening at a top end for fluids to enter and one or more openings at a bottom end for fluids from below the cup to enter said inner bell;

d. an outer bell closed at a top end and open at a bottom end which covers and surrounds said inner bell with an inner annular space between said outer bell and said inner bell and wherein said outer bell is surrounded by said cup with an outer annular space between said outer bell and said cup and wherein said outer annular space provides a channel for fluids to flow from said cup into said outer bell.

4. The automatic bell siphon of claim 3, wherein said outer bell is mounted on top of said inner bell with a spacer abutting a top of said inner bell and abutting and supporting an inner surface of a cap connected to said outer bell.
